UNITED STATES PATENT OFFICE.

JOHN A. HOUCK, OF DETROIT, MICHIGAN, ASSIGNOR OF ONE-HALF TO
JOHN C. GROUT, OF SAME PLACE.

AUTOMATIC GREASE-CUP.

SPECIFICATION forming part of Letters Patent No. 312,204, dated February 10, 1885.

Application filed May 13, 1884. (No model.)

To all whom it may concern:

Be it known that I, JOHN A. HOUCK, of Detroit, county of Wayne, State of Michigan, have invented a new and useful Improvement 5 in Automatic Grease-Cups; and I declare the following to be a full, clear, and exact description of the same, such as will enable others skilled in the art to which it pertains to make and use it, reference being had to the accompanying drawings, which form a part of this specification.

My invention consists in the combination of devices and appliances hereinafter specified, and more particularly pointed out in the 15 claims.

In the drawings, Figure 1 is a vertical section of a device embodying my invention. Figs. 2 and 3 are variations.

My invention relates to an automatic grease- 20 cup adapted to feed the grease continuously.

Heretofore grease-cups as commonly constructed have required the attention of the attendant to see that they are working properly and to apply pressure from time to time as it 25 may be needed.

In practice it has been found that in certain locations it has been impracticable to apply the necessary pressure while machinery is in motion—as, for instance, a cup connected 30 with a crank-pin—necessitating a stoppage of the machinery for this purpose.

It is the object of my invention to overcome these difficulties, and to construct a cup that shall feed continuously and automatically 35 without requiring such attention.

I accomplish my object as follows:

As illustrated in the accompanying drawings, A represents the cup.

B represents any suitable cap, adapted to be 40 engaged upon the cup. This cap may be engaged upon the cup by screw-connections, or it may be engaged thereon in any other suitable way—as, for instance, by a catch or ratchet mechanism.

45 I would have it understood that I do not limit myself to any specific way of securing the cap in place upon the cup.

C is a movable plate, provided in any suitable manner with an air-tight joint at its periphery. As shown, the plate is cut away

upon its edge to receive a suitable packing to make the joint air-tight.

a is the outlet-orifice of the cup.

The operation of the device is as follows: The cap being removed, the cup is filled with 55 grease. As the plate C, located within the cap, is forced inward, it is evident that a quantity of air will be confined and compressed in its rear in the chamber F. It will be seen, therefore, that as the grease feeds from the 60 cup the expansion of the compressed air in the rear of the plate C will exert a constant pressure upon the grease to force it from the cup, this action being automatic. The construction necessary to secure this compression of 65 air may be modified in many ways. As shown in Fig. 1, an additional plate, C', may be employed, connected to the plate C by an intervening stem, C', in any proper manner, in order to extend the pressure of the air to a 70 greater distance in the cup. So, also, as shown in said figure, an additional movable plate, D, may be employed in connection with the plate C or plates C and C', said partition D having an air-tight connection in the cap, and provided with a screw-cut stem, D', tapped through 75 the cap, by means of which the compression may be increased in the rear of the plate C; or, moreover, as shown in Fig. 3, the plate C may be dispensed with entirely, if preferred, 80 and the cap be provided with any suitable air-pump, E, having its piston E' extending through the top of the cap, the construction being such that air may be forced into the top of the cap, and thereby be compressed in the 85 compressed-air chamber F, the force of the air being exerted directly on the contents of the cup, although an intervening partition may be located above the contents, if it should be found desirable. I prefer, also, to secure upon 90 the nozzle of the cup any suitable regulating-valve, as shown at E". The rate of feed may be regulated, if desired, by means of the valve-stem. I design to employ the cup either with or without a regulating-valve, as may be preferred.

What I claim is—

1. The combination of a grease-cup, a cap adjustably secured thereon and provided with a movable partition, and additional mech- 95 anism.

ism for compressing the air above the parti-
tion, substantially as described.

2. A grease-cup provided with an air-pump
adapted to pump air into the cup and com-
5 press the same above the contents of the cup,
substantially as described.

3. The combination, with a grease-cup hav-
ing a single reservoir, and an air-chamber
10 above the contents of the cup, of an air-pump
to compress the air above the contents of the
cup, substantially as described.

4. The combination, with a grease-cup hav-
ing a removable cap and an air-chamber above
15 the contents of the cup, of an air-pump lo-
cated in the cap to compress the air above the
contents of the cup, substantially as described.

5. A grease-cup provided with an air-pump
adapted to pump air into the cup and to com-
20 press the same above the contents of the cup,
and a valve for regulating the outflow from the
cup, substantially as described.

6. The combination, with a grease-cup, of a

cap adjustably secured thereon, said cap pro-
vided with a movable plate having an air-tight
connection in said cap, and in connection there-
with a movable plate adapted to be located
over the contents of the cup, said plates hav-
ing a connection whereby the expansion of the
air behind the plate in the cap will exert a
pressure upon the contents of the cup, and
30 mechanism for compressing air above the
plates, substantially as described.

7. The combination, with a grease-cup, of a
cap adapted to be adjustably secured thereon,
said cap provided with a compressed-air cham-
ber, said cup provided with a regulating-valve,
35 substantially as described.

In testimony whereof I sign this specifica-
tion in the presence of two witnesses.

JOHN A. HOUCK.
